UNITED STATES PATENT OFFICE.

NORMAN B. LAWSON, OF MUSKEGON, MICHIGAN.

WATERPROOF SUIT.

SPECIFICATION forming part of Letters Patent No. 760,880, dated May 24, 1904.

Application filed January 15, 1904. Serial No. 189,215. (No model.)

To all whom it may concern:

Be it known that I, NORMAN B. LAWSON, a citizen of the United States, residing at Muskegon, in the county of Muskegon and State 5 of Michigan, have invented certain new and useful Improvements in Waterproof Suits, of which the following is a specification.

The object of this invention is to construct a suit which will entirely inclose the body of 10 the wearer and made of waterproof material and provided with an air-inlet and a pump for removing water from within the suit should any leak in and in means for pumping air to the occupant.

15 The accompanying drawing shows a perspective view of my improvements.

The suit has the body portion 1 open in the back in order that the wearer may get into it. The opening is closed by overlapping flaps 2.

20 The arm-receptacles 3 are integral with the body portion, also the leg-receptacles 4.

A dome 5 on the back of the suit is of heavier material than the remainder of the suit and has an opening 6. A cup-shaped cap 7 is 25 placed over the opening, so that should water wash over the cap a seal would be effected, thereby excluding all water from the interior of the suit, but allowing air to gain access through the opening 6.

30 In the lengthwise direction of the suit and on its front side and inner face extends a tube 8, having two branches 9 and 10 extending to about the knees of the suit. A three-way cock 11 is located at the junction of the branches 35 with the main portion. The handle 12 of the three-way cock projects through the suit at a point within reach of the wearer.

A plunger-pump 13 is located within the suit and supported thereby, having its handle 14 projecting through the suit within reach 40 of the wearer. The pump has a connection with the main tube 8 and has an opening 15 communicating with the outside of the suit.

Should the suit spring a leak, the water will 45 settle to the lowest point, being about the knees, and by means of the pump and three-

way cock the water can be pumped from around either leg, thereby preventing the suit filling with water.

By the employment of my improved suit a 50 person may stay in the water a great length of time without dying from exposure and may be able to take a line ashore and rescue others on board a vessel.

To the head portion of the suit is connected 55 a hinged face portion 16, connected by a cam-lever 17. A bag 18 is connected with the suit and located under the arm, so that a movement of the arm will compress it, and when the pressure is removed it will expand. A 60 pipe 19, having a valve 20, communicates with the bag and extends into the dome 5, and a pipe 21, provided with a valve 22, communicates with the bag and having its free end communicating with the face portion 16 of the 65 head.

A tube 23 communicates with the dome 5, and with a section 24, adapted to be placed in the mouth of the occupant of the suit. A valve 25 is located in this tube near the section 24. A 70 tube 26 extends through the head portion of the suit, and its other end communicates with the section 24, having a valve 25 near the section 24. With the section 24 in the mouth of the occupant of the suit air may be drawn 75 through the tube 23 from the dome 5 and discharged through the tube 26, and when the bag 18 is in operative condition air may be forced into the face portion of the head-covering, thereby supplying air to the occupant. 80 By this arrangement the occupant of the suit can pump water out leaking into the suit, and can supply himself with fresh air, and can see out through the openings in the covered face portion covered by the glass 28.

I claim as my invention—

1. A waterproof suit having arm and leg receptacles integral therewith, a dome on the back portion of the suit having an opening and a cap over the opening.

2. A waterproof suit having arm and leg receptacles integral therewith, tubes leading to

the leg portions of the suit, and a pump having a connection with the tubes, and an education-port to the pump.

3. A waterproof suit having a head portion and a face-covering, a section of tube adapted to be placed in the mouth of the occupant of the suit, a tube connecting the mouth-section with the outer air and provided with a check-

valve, and a tube connecting the mouth-section and provided with a check-valve acting as 10 a discharge.

NORMAN B. LAWSON.
